United States Patent Office

Des. 187,284
Patented Feb. 23, 1960

187,284

TOY SPUR

Carl Ayala and Bayard C. Reed, Chicago, Ill., assignors to
Marvin I. Glass, Chicago, Ill.

Application March 7, 1958, Serial No. 49,952

Term of patent 3½ years

(Cl. D34—15)

Figure 1 is a perspective view of a toy spur, showing our new design;

Figure 2 is a side elevational view; and

Figure 3 is a plan view thereof.

We claim:

The ornamental design for a toy spur, substantially as shown.
